SPEED CONTROLLED GOVERNOR

Max Hurst, Stuttgart, Germany, assignor to
Robert Bosch, G. m. b. H., Stuttgart, GermanyApplication March 1, 1949, Serial No. 79,013
In Germany October 1, 1948

5 Claims. (Cl. 264—3)

1

This invention relates to a speed-controlled governor, more particularly for injection pumps, whose movable member acts upon a delivery control member through an intermediate lever with a transmission ratio which can be adjusted through a crank arm. In governors of this type it is advisable to support the crank arm to be jointed to the intermediate lever in a part of the casing forming the closing portion of the governor casing or at the front wall of said casing. This arrangement renders it difficult when fitting or removing this casing part to assemble or detach the movable parts of the mechanism.

It is the object of the invention to design a governor of the type referred to in such a manner that the assembling is facilitated and combined with an easy manufacture and machining of the components of the governor which are to be jointed together and of their casing while at the same time ensuring a faultless operation of the governor.

According to the invention this task is solved in such a way that the guide at the intermediate lever which is required for transmitting the adjusting movements of the crank arm, is made open at one end so that when attaching or detaching the casing part provided with the crank arm bearing, the crank arm part serving as a lever joint can be engaged with, or disengaged from, the intermediate lever through this open end of the guiding surface.

According to a particularly advantageous modification of the invention the part of the intermediate lever facing the governor sleeve has a cylindrical hollow space which is open at least at its upper side facing the delivery control member and whose wall forms the sliding surface for a cylindrical slide as well as a lateral slot which preferably is also open in an upward direction and traversed by a pin provided at the crank arm and jointedly engaging the cylindrical slide. Thus, the assembling of the parts is particularly facilitated and a reliable guide face is formed between the lever arm and the intermediate lever and first of all the movement of this intermediate lever is almost free from friction and jamming is safely prevented. This last-mentioned property can be fostered additionally in centrifugal governors of the conventional type with a slide block arranged between two annular shoulders of a regulating sleeve in such a way that the slide block which is supported on the governor shaft with sufficient radial play and engaged by an arm of the intermediate lever, is guided for longitudinal sliding on a pin which is to be inserted in the front wall of the governor casing, parallel-

2

ly to the governor shaft. This pin takes the pressure on the support of the intermediate lever and the parts jointed thereto and relieves the governor sleeve and the delivery control member from these stresses which otherwise would impair the accuracy of the governor in operation. Therefore, the application of such a guide member is to be recommended in speed governors in which the governor sleeve is coupled with the regulating member through an intermediate lever and a link.

Further objects and features of the invention will be seen from the following detailed description in connection with the accompanying drawing showing by way of example and purely schematically some embodiments of the invention and in which:

Fig. 1 is a longitudinal section of a first embodiment;

Fig. 2 is a side view showing a detail of the second embodiment;

Fig. 3 is a fragmentary longitudinal section on the line III—III of Fig. 4 of the third embodiment, and

Fig. 4 is a cross sectional view on the line IV—IV of Fig. 3, the crank arm being shown in a position swung upwards into a higher position than in Fig. 3.

Similar reference numerals denote similar parts in the different views.

Referring now to the drawing in greater detail, it will be seen that a driver 12 is secured on a cam shaft 10 of an injection pump 11, shown schematically, two angle levers 13 being jointed to said driver. One arm of this lever engages a centrifugal weight 15. Through each of the two centrifugal weights projects a pin 14 in a radial direction, bearing at its end a spring plate 14a against which bears, in a manner known per se, an idle run spring 16 and a maximum speed spring 17. The other arm of each angle lever 15 is jointed to an associated radial journal 19 of a governor sleeve consisting of a pin 20 with two annular collars or flanges 21 which pin is longitudinally guided in a recess of driver 12. Between these annular collars is a so-called slide block 22 with two joint pins 23 engaged by a bifurcated arm of the intermediate lever 24. The other arm of this lever is jointed to a delivery regulating member (governor rod) 25.

A pin 28 of a crank arm 30 secured on a shaft 29 projects into a longitudinal slot 27 of the intermediate lever 24 which slot is open at one side, i. e., in an upward direction. The shaft 29 is supported in a casing part 31 covering the governor and can be swung by an adjusting lever or mem-

ber 32 within a range which is defined by two adjustable stops 33 and 34. In the "idle run position" shown in Fig. 1 the crank arm engages the stop 33 and the crank pin 28 forming the pivot bearing of the intermediate lever 24 is so close to the governor rod 25 that the transmission ratio of the intermediate lever for the transmission of the movement between governor sleeve 20, 21 and governor rod 25 is a relative minimum. On the other hand, when the crank arm is swung so far that it engages stop 34, the pin 28 moves relatively far towards the governor sleeve. Thus a considerably larger transmission ratio of the intermediate lever 24 is obtained in such a way that large strokes of the governor rod are obtained already with relatively small strokes of the governor sleeve 20, 21.

Through the slot 27 which is open towards the governor rod 25 the crank pin 28 can easily be engaged with the intermediate lever 24 when attaching casing part 31 to the injection pump 11.

As will be seen from Fig. 2, the slot 27 for inserting pin 28 can also be formed with a mouth end which is open at one edge of the intermediate lever 24, for introducing pin 28.

In the embodiment as per Figs. 3 and 4 a cylindrical hollow space 34 is provided in the intermediate lever 24, at the inner wall surface of which is guided a cylindrically shaped slide 38, into which projects, through a sufficiently wide wall slot 27, the crank pin 28 to which the cylindrical slide 38 is jointed. The governor rod 25 is connected, through a link 26, with the intermediate lever 24. The weight of the lever thus rests upon the slide block 22, 23, so that the guide surface of the governor rod is relieved from this weight. In order to relieve also the governor sleeve 20, 21, from this weight, the slide block 32 supported with ample play on the governor sleeve 20, 21 is shaped so as to project unilaterally from the sleeve and provided with a bore into which engages a guide pin 35 inserted in the front wall of the casing part 31 parallel to the governor sleeve. Through this guide member the pressures on the support originating from the intermediate lever 24 and the link 26 are taken up at a particularly favorable position where no high frictional resistances can be produced. There are no lateral shearing forces acting upon the governor rod 25 and on the governor sleeve 20, 21, which forces could give rise to increased friction or even to jamming of these parts in their guides.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a speed-controlled governor, in combination a governor sleeve, a cylindrical slide, an intermediate lever, a crank arm having a pin and adapted to adjust the transmission ratio of said intermediate lever, a casing part forming the bearing for said crank arm, a delivery control member, and an adjusting member adapted to act upon said delivery control member through said crank arm and said intermediate lever, said intermediate lever provided with a portion, facing said governor sleeve, which has a cylindrical hollow space which at least at its upper side facing the delivery control member is open and

whose wall forms the slide surface for said cylindrical slide and which has at least one lateral slot which is also open in an upward direction through which slot projects said crank arm pin which is jointed to said cylindrical slide in such a way that, when attaching or detaching said casing part provided with the crank arm bearing, the crank arm part serving as a lever joint can be engaged with, or disengaged from, said lever through said open end of the guide.

2. In a governor, in combination, a governor sleeve provided with two annular shoulders, a slide block arranged between the two annular shoulders of said governor sleeve, an intermediate lever pivotally mounted intermediate its ends to provide a first lever arm and a second lever arm and whose first arm engages said slide block, a delivery control member to which the second arm of said intermediate lever is connected, a governor shaft, a governor casing, and a pin adapted to be inserted in the front wall of said governor casing parallel to the governor shaft, said slide block being slidable on said pin.

3. In a governor, in combination, a governor sleeve provided with two annular shoulders, a slide block arranged between the two annular shoulders of said governor sleeve, an intermediate lever pivotally mounted intermediate its ends to provide a first lever arm and a second lever arm and whose first arm engages said slide block, a delivery control member to which the second arm of said intermediate lever is connected, a link connecting said delivery control member with said second arm of said intermediate lever, a governor shaft, a governor casing, and a pin adapted to be inserted in the front wall of said governor casing parallel to the governor shaft, said slide block being slidable on said pin.

4. In a speed-controlled governor, in combination, a governor sleeve provided with two annular shoulders, a slide block arranged between the two annular shoulders of said governor sleeve, an intermediate lever pivotally mounted intermediate its ends to provide a first lever arm and a second lever arm and whose first arm engages said slide block, a delivery control member to which the second arm of said intermediate lever is connected, a governor shaft, a governor casing, and a pin adapted to be inserted in the front wall of said governor casing parallel to the governor shaft, said slide block being slidable on said pin, a crank arm adapted to adjust the transmission ratio of said intermediate lever, said crank arm including a part serving as a pivot for said intermediate lever, a casing part forming the bearing for said crank arm, and an adjusting member adapted to act upon said delivery control member through said crank arm and said intermediate lever, said intermediate lever including a guideway for the adjusting movements of said crank arm, said guideway being open at least at one end in such a way that, when attaching or detaching said casing part provided with the crank arm bearing, the crank arm part serving as a pivot for said lever can be engaged with, or disengaged from, said lever through said open end of the guide.

5. In a speed-controlled governor, in combination, a governor sleeve provided with two annular shoulders, a slide block arranged between the two annular shoulders of said governor sleeve, an intermediate lever pivotally mounted intermediate its ends to provide a first lever arm and a second lever arm and whose first arm

engages said slide block, a delivery control member to which the second arm of said intermediate lever is connected, a governor shaft, a governor casing, and a pin adapted to be inserted in the front wall of said governor casing parallel to the governor shaft, said slide block being slideable on said pin, a crank arm having a pin and adapted to adjust the transmission ratio of said intermediate lever, a casing part forming the bearing for said crank arm, and an adjusting member adapted to act upon said delivery control member through said crank arm and said intermediate lever, said intermediate lever provided with a portion, facing said governor sleeve, which has a cylindrical hollow space which at least at its upper side facing the delivery control member is open and whose wall forms the slide surface for said cylindrical slide and which has at least one lateral slot which

5 preferably is also open in an upward direction through which slot projects said crank arm pin which is jointed to said cylindrical slide in such a way that, when attaching or detaching said casing part provided with the crank arm bearing, the crank arm part serving as a lever joint can be engaged with, or disengaged from, said lever through said open end of the guide.
